UNITED STATES PATENT OFFICE.

KENNETH HOWIE, OF NORRISTOWN, PENNSYLVANIA, ASSIGNOR TO WILDMAN MFG. CO., OF NORRISTOWN, PENNSYLVANIA, A CORPORATION OF PENNSYLVANIA.

LOOP-TRANSFER MECHANISM FOR KNITTING MACHINES.

Application filed May 11, 1922. Serial No. 560,098.

To all whom it may concern:

Be it known that I, KENNETH HOWIE, a citizen of the United States, and resident of Norristown, in the county of Montgomery, in the State of Pennsylvania, have invented certain new and useful Improvements in Loop-Transfer Mechanism for Knitting Machines, of which the following is a specification.

10 The invention is designed to produce ribbed tops for transfer to the needles of a stocking knitting machine. The ribbed tops are knit in string work with alternating portions of plain fabric between the 15 ribbed tops and with welts suitably disposed. The last course of rib knitting has its dial loops transferred to the cylinder needles and then the plain fabric portion is knit on the cylinder needles. The resultant 20 product has the last course of the cylinder and dial loops in registration, each pair being interknit with a stitch of the plain fabric so that in transferring the ribbed top to the needles of the stocking machine, 25 it is necessary for the operative to perform only one half of the usual transfer actions because the rib loops are transferred in pairs, i. e., a dial loop and its companion cylinder loop. The courses of plain fabric 30 which are attached to the rib fabric are ravelled out after the transfer has been effected.

The invention consists in the features and combination and arrangement of parts hereinafter described and particularly pointed out in the claims.

In the drawings:—

Fig. 1 is a plan view of so much of a knitting head as is necessary to lead to an 40 understanding of the invention.

Fig. 2 is a plan view in the nature of a diagram showing the cams of the dial and loop transfer elements, as though the supporting plate and ring for these cams had 45 been removed.

Fig. 3 is a view of the cylinder cams developed.

Fig. 4 is a vertical sectional view of one-half of the needle cylinder and the dial with 50 their cams and with the supporting ring or bed for the transfer elements and their cams.

Fig. 4a is a detail view of a part of the

cylinder cam casing and the cam ring of the transfer elements with the means which 55 connect them together.

Figs. 5 to 11 are views of the needles and transfer elements in the various positions they assume at different steps in the operation of transferring the dial loops to the 60 cylinder needles and performing plain knitting on the cylinder needles.

Fig. 12 shows details of the needle and transfer elements.

Fig. 13 is a view showing the arrangement of the loop lifting member.

The invention is shown as carried out on a machine having rotary cams, but it will be understood that the invention is not limited in this respect, as it may be carried 70 out in connection with a rotary needle carrier type of machine.

In the drawings, 1 is the fixed base ring of the knitting head supporting as a fixture, the needle cylinder 2. The rotary needle 75 cam box 3 is driven, as is customary, through a gear, not shown, meshing with the bevelled gear 4 on the base of the cam box 3.

The needle dial is supported by a dial 80 post, as is usual, and any suitable means may be employed for holding the dial against rotation, such as dogs, as have been employed heretofore, or the dogless mechanism disclosed in reissue Letters Patent of 85 the United States of G. L. Ballard, March 28, 1916, No. 14,092, may be used and in the present description we will assume that the latter mechanism is employed. The dial cap or cam plate 6 is connected with the cam 90 ring 16 of the loop transferring elements 14 by a link 6' and this cam ring 16 is connected with and is driven by the cylinder cam ring 3. For this purpose as shown in Fig. 4a, a pin 7 is fixed in the cam ring 16 95 and depends between ears of a block 7' which is fixed by a screw 7a to a post 7b fixed in the cylinder cam ring 3. Screws 7c serve to adjust the cam ring 16 in proper circumferential relation to the cam ring 3. 100

From this construction, it will be seen that the rotating cylinder cam ring 3 drives the cam ring 16 of the transfer elements 14, and this in turn drives the dial cam plate 6, so that all of these cams rotate in unison. 105

At 8, dotted line Fig. 1 is shown the forked

bracket or arm which engages the pin 8' of the link 6' which latter, as before stated, connects the dial cap with the cam ring 16 of the transfer points or hooked elements.

5 This forked arm 8 is for rotating the center plate of the dogless attachment (said plate being indicated at 6 in the said Ballard patent).

10 The bed 9 for these transfer elements is fixed by screws 9' and clamping washers 10 to the annular rib or extension 11 of the needle cylinder and is thus held stationary.

15 All of the beds of the cylinder needles, dial needles and transfer elements 14 are slotted for guiding the elements carried thereby.

The cylinder needles are the ordinary latch needles.

20 The dial needles are of the ordinary latch type excepting that in the exterior surface of their hooks the said dial needles are provided each with a recess 12 adapted to receive the upstanding point 13 of the loop transfer elements 14. These loop transfer 25 members are in the form of metal pieces slidably mounted in the radial grooves of the ring or bed 9, and they have butts 15 for engaging the cam groove of the cam ring 16.

30 *Cams for needles and dial loop transfer elements.*

The cams for the cylinder needles are mostly of ordinary form including, however, a cam 3^x for advancing the cylinder needles to take on the dial loops. The stitch cam 3^a of this set is adapted to be depressed for making a loose course and as in ordinary practice, this is accomplished by a striker 40 or roller 17 which, as in the Wildman type of machine, is adapted to be raised to different elevations by pattern mechanism to be struck by contact arms carried by the cam box, and actuating controlling means 45 of the cams. At 18, Fig. 1, is shown a pair of these arms geared together to operate on arm 18' which determines the position up or down of the stitch cam, as in ordinary practice.

50 The dial cam set includes an advancing or wing cam 19 of substantially ordinary form pivoted to the cam cap or carrier 6 at 19'. 20 is the dial stitch cam. 21 is the cam for projecting dial needles for loop transferring. This cam is pivoted to the cap 6 at 21'. 22 is the transfer retracting cam, which comes into use during the transfer of stitches from the dial to the cylinder needles, and 23 is a cam for advancing the dial 60 needles to have their latches opened by a latch opener, this latch opening action occurring after the dial loops have been transferred leaving the needles bare.

The cams for the transfer elements include an advancing cam 25 pivoted at 25',

and a fixed retracting cam composed of two inclines 26, 26', with a dwell 27 between them.

The pivoted cams, i. e., the wing cam 19, the transfer projecting cam 21, and the advancing cam 25, of the loop transfer elements, are all operated to their different positions by contact arms on the rotary cam box striking the roller 17 when this is moved vertically by pattern mechanism into the plane of travel of these various arms.

Fig. 1 shows two contact arms 28, 28' inter-connected by teeth 29 for giving reverse movements to a link 30 through an arm 31. These arms 28, 28' lie in different horizontal planes. At 32, 32^x are contact arms at different elevations to strike the roller 17 when this is moved into their respective paths of travel, and these arms, which are geared together, control through 35 an arm 33, arm 34, link 35 and arm 36, the positions in or out of the cams 21 and 25.

Connection to the pivoted arms is effected by pins 37, 38 and 39 through slots in the cam cap or ring, as shown in Fig. 1. The two cams 21 and 25 are operated from the same set of connections from the contact arms 32, 32^x.

Sequence of movements of knitting elements and dial loop transfer elements.

Normally, during ordinary rib knitting the transfer elements 14 which are to transfer the dial loops of the last course of rib knitting of the top or cuff onto the cylinder needles, are retracted and lie with their points 13 slightly back within their guide grooves in the bed 9. In making the last course of rib knitting the stitch cam for the cylinder needles is depressed for making a loose course. On the next revolution the dial wing cam, or needle advancing cam, is set in its inward position, i. e., toward the center of the machine so that the dial needles will not be advanced for knitting, but they will hold their old loop. The dial is then racked or shogged circumferentially so that the dial needles will occupy the same vertical planes in which the cylinder needles lie instead of lying in radial planes between the radial planes in which the cylinder needles lie. This shogging action may be performed in various ways, for instance, through an arm 40 connected with the dogless head as shown by screws 41, dotted lines Fig. 1, said arm 40 being swung around the desired distance by an arm 42 having movement about the center 43 and operated by an arm 44 and link 45 from the pattern mechanism of the machine, not shown, but of any general form well known to those skilled in the art.

The arm 42 has a pin 46 to bear on a lug 47 of the arm 40. A spring 48 returns the dial to normal position from its shogged position. This shogging of the dial, gener- 130

ally speaking, is common in the art. It is forecasted in the patent of Butz No. 1,012,982, December 26, 1911, though in that patent it was proposed that it be done by hand.

5 This shogging of the dial takes place in the last half of the same revolution in which the wing cam 19 is set inwardly, as above described. On this same revolution, the dial cam 21 is moved to the position shown in Fig. 2 to project the dial needles for having their loops transferred to the cylinder needles, and simultaneously with the setting of this cam 21, the advancing cam 25 of the transfer elements is thrown to advanced position, or in other words, towards the center of the machine because both cams 21 and 15 25 are operated through the same connection from the contact arm 32.

One revolution now takes place to transfer the loops from the dial needles to the cylinder needles. When the transfer of dial loops has been effected, the dial is shogged back to normal position so that its needles instead of lying in the radial planes of the 25 cylinder needles, will lie over the spaces between them and the cylinder needles can then perform knitting operations to make plain fabric. The knitting of the plain fabric on the cylinder needles may take 30 place for any desired number of revolutions, say, six courses of plain fabric are knit. During this time the latches of the dial needles are opened by a suitable latch opener, and for this purpose the dial needles 35 are advanced by the cam 23. After this the dial wing cam 19 is restored to normal outward position to advance the dial needles to receive yarn and knit rib fabric in conjunction with the cylinder needles.

40 Transferring loops.

The different steps in the transferring operation are illustrated in Figs. 5 to 11 inclusive.

45 In Fig. 5 the transfer members are in normal retracted position with their upstanding points 13, slightly back within the guide grooves of the bed 9, say $\frac{1}{16}$ of an inch. The loose course having been formed and 50 the dial wing cam set in to prevent further knitting on the dial needles, the dial is shogged to make the dial needle planes coincide with the radial planes in which the loop transfer members and the cylinder needles lie. The dial needles are then projected as in Fig. 6 by cam 21, so that their hooks 12' will enter slightly the guide grooves of the bed 9 of the loop transfer members. To insure the entry of the hooks 55 of the dial needles into these grooves, the mouths of said grooves may be slightly flared. These projected dial needles will receive in the notches 12 of their hooks the points 13 of the transfer members, as indicated in Fig. 6, and they will have been

projected so far that their latches will shed their loops onto the needle stems back of the latches. The engaged elements, i. e., dial needles and loop transfer members, now move inwardly towards the center of the machine as shown in Fig. 7 until the hooks of the dial needles lie slightly back of the mouths of the guide grooves of the dial, the dial needles being pushed into this position by the loop transfer elements. The dial loop in this action just described will be cast over the needle hook and the point 13 of the transfer element now embedded there-in and will lodge in the recess 13' of the transfer element adjacent the base of the 70 75 80 upstanding point 13. During this action of course, the dial needle latch will be closed.

The loop transfer element with the dial loop hanging in its recess 13' will now recede outwardly part way by the action of cam incline 26 and this loop will be held directly over the cylinder needle, the fabric take-up, together with the transfer element determining this location of the dial loop. The cylinder needle is now projected upwardly 85 90 through its old loop and the dial loop but it is not projected far enough to shed these loops from its latch onto its stem. The projection is sufficient, however, to get the hook of the cylinder needle above these loops and the upward movement of the needle will lift the dial loop off from the point 13 of the transfer device. The actions just described take place at the dwell between the inclined cam surfaces 26, 26'. Should the dial loop not be lifted from the transfer needle, the loop will be raised from the transfer device by a loop shedding member 50 consisting of a wire attached to the 95 cylinder cap and rotating therewith around the 100 105 needle circle.

The cylinder needle having received the transferred dial loop, now recedes and this loop is now taken by the hook of the cylinder needle. At about this same time the loop transfer member recedes to normal position by the action of cam incline 26'. The dial now is shogged back to normal position. The cylinder needle will now be advanced by its advancing cam to take new 110 115 120 125 yarn and make plain fabric for a number of courses. The wing cam then will be restored to operative position and the dial needles will be operated to make rib fabric in conjunction with the cylinder needles, thus completing one cycle of operation which is repeated to make the string work ribbed top alternating with the courses of plain fabric.

The loop lifting member 50 is so disposed as to cause its forward end to take under the loop on the transfer member and raise it over the point thereof. I do not limit myself herein to the use of this loop lifting device. It is employed as a supplemental fea-

ture. The natural effect of the rising cylinder needle is to lift the loop from the transfer element.

This specification with the accompanying drawing, being addressed to those skilled in the art of knitting, it will be understood that changes may be made within the skill of the expert machine builder without departing from the principles of the invention. The specification and drawings are therefore to be taken in an illustrative sense and not as restrictive upon the scope of the invention, which latter is defined by the accompanying claims. As above stated, welts 15 may be formed in the fabric at suitable points.

I claim:

1. A knitting machine for making rib and plain fabric having two sets of needles working in interspaced planes for making rib fabric, a set of transfer members for transferring the loops of one set of needles to the needles of the other set and arranged to work in the same planes with the set of needles which are to receive the transferred loops, means for shogging the first set of needles into line with said transfer members, means for reciprocating the said needles and transfer members, said transfer members taking the loops from the shogged needles and holding them in position to be taken therefrom by the other set of needles, substantially as described, said transfer members being latchless, substantially as described.

2. In combination in a knitting machine two sets of latch needles cooperating to make rib fabric, means for shogging one set of needles into position to have their loops transferred to the needles of the other set, a series of latchless transfer members to receive the loops cast from the shogged needles, said transfer members holding the cast loops to be penetrated by the needles of said other set, the movement of said needles removing the loops from the transfer members, substantially as described.

3. In combination, in a knitting machine two series of latch needles for making rib fabric, and a series of latchless transfer members for receiving the needle wale loops from one series of needles and holding them to be penetrated and taken therefrom by the needles of the other series, said transfer members, as a series, being arranged opposite the series of needles from which they receive the loops.

4. In combination, in a knitting machine, two series of latch needles, a series of latchless loop transfer members, means for advancing the needles of one series and the transfer members until the hook ends of the said needles and the ends of the transfer members engage, and for then retracting the said needles while further advance of the

transfer members takes place to maintain the engagement of said needles and members until after the loops are cast from said engaged needles onto the transfer members, and for retracting the transfer members to 70 present the said loops to the needles of the other set, while the needles which have cast their loops remain retracted, and means for advancing the needles of said other set to penetrate and take off the cast loops from 75 the transfer members, substantially as described.

5. In combination, in a knitting machine, two series of latch needles, a series of latchless loop transfer members, means for advancing the needles of one series and the transfer members until the hook ends of the said needles and the ends of the transfer members engage, and for then retracting the said needles while further advance of the 80 transfer members takes place to maintain the engagement of said needles and members until after the loops are cast from said engaged needles onto the transfer members, and for retracting the transfer members to 85 present the said loops to the needles of the other set, while the needles which have cast their loops remain retracted, and means for advancing the needles of said other set to penetrate and take off the cast loops from 90 the transfer members, said transfer members being at rest when the loops are taken therefrom and thereafter retracting to their normal positions, substantially as described.

6. A knitting machine having two series 100 of latch needles for making rib fabric, a series of latchless transfer members to receive the needle wale loops cast over the hooks of one set of needles and arranged out beyond the said set and holding said loops to be received by the other set of needles as the latter advance, and means for giving the needles and transfer members their necessary movements, substantially as described.

7. A knitting machine having two series 105 of latch needles for making rib fabric, a series of latchless transfer members to receive the needle wale loops cast from one set of needles and holding said loops to be received by the other set of needles as the latter advance, means having relative movement to and along the series of transfer means for delivering the loops from the transfer means, and means for giving the 110 needles and transfer members their necessary movements, substantially as described.

8. In combination, in a knitting machine, two series of latch needles, a series of latchless loop transfer members, means for advancing the needles of one series and the transfer members until the hook ends of the said needles and the ends of the transfer members engage, and for then retracting the 115 said needles while further advance of the 120

- transfer members takes place to maintain the engagement of said needles and members until after the loops are cast from said engaged needles onto the transfer members, and for retracting the transfer members to present the said loops to the needles of the other set, while the needles which have cast their loops remain retracted, and means for advancing the needles of said other set to receive the loops from the transfer members, substantially as described. 65
- 5 9. In a rib knitting machine two series of latch needles, a series of hooked but latchless transfer members with means for advancing them to lay their hooked ends against the hook ends of advanced needles of one set and to follow up and maintain said engagement as the said advanced needles retract to make said transfer members receive the loops cast from said needles, said transfer members then retracting to a position to hold said loops in position to be penetrated by the needles of the other set, the said loops being delivered to the last 70
- 10 20 25 30 35 40 45 50 55 60 65 70 75 80 85 90 95 100 105 110 115 120
- members receive the loops over the upwardly directed hooks of the transfer members, substantially as described.
10. In a rib knitting machine, two series of latch needles for making rib fabric, one of said series having notches in the exterior of their hook ends, a series of transfer members having their ends adapted to enter said notches to receive the loops cast from said needles, said loops being held by said members to be received by the needles of the other series and means for giving the needles and transfer members their movements, substantially as described. 125
11. In combination in a knitting machine, two series of latch needles for making rib fabric, the needles of one series having notches in their hook ends, and transfer members having hooks to lay in said notches with the points of said hooks directed to the front or latch side of said needles, said hooked transfer members receiving the cast loops from the said needles, and holding the same in position to be penetrated by the needles of the other set which receive them, substantially as described. 130
12. In combination, in a circular knitting machine, cylinder and dial latch needles, for making rib fabric, and a series of latchless transfer members surrounding the circle of dial needles and mounted to reciprocate in line with said dial needles, to engage said needles when advanced and follow up the retracting movement of said dial needles to receive the loops cast therefrom, said transfer members then retracting part way to position the said loops to be penetrated by the cylinder needles, while the dial needles remain retracted, said cylinder needles receiv-
- ing the loops from the transfer members, and means for giving the needles and transfer members their movements in transferring the loops and giving the cylinder needles their movements for making plain fabric, substantially as described. 135
13. In combination, in a knitting machine, latch needles, having notches in the outer rounded sides of their hook ends, and loop transfer members having hooks to lie in said recesses, the inner sides of said hooks being inclined from their base portions towards the ends of the members to facilitate the delivery of the loops from said members, substantially as described. 140
14. In combination, two series of needles for producing rib fabric, and a set of members for transferring the loops from the needles of one set to the needles of the other set for making plain fabric on the latter, said transfer means being latchless and engaging end to end the needles of the set first mentioned to receive the loops cast therefrom. 145
15. In combination, two series of needles for producing rib fabric, and a set of members for transferring the loops from the needles of one set to the needles of the other set for making plain fabric on the latter, said transfer members being latchless and engaging end to end the needles of the set first mentioned to receive the loops cast therefrom, said transfer members retracting after receiving the cast loops to position them to be taken by the needles of the other set, substantially as described. 150
16. In combination, two series of needles for producing rib fabric, and a set of members for transferring the loops from the needles of one set to the needles of the other set for making plain fabric on the latter, said transfer members being latchless and engaging end to end the needles of the set first mentioned to receive the loops cast therefrom, said transfer members retracting after receiving the cast loops to position them to be taken by the needles of the other set, one of the sets of devices being shogged to align it with the devices of another set, substantially as described. 155
17. In combination, two series of needles for making rib fabric, a series of latchless loop transfer elements, means for operating said elements against the needles of one series to receive the loops cast therefrom and thereafter to position said loops to be penetrated by the needles of the other series, and a loop lifter device for raising the loops from the transfer elements to be lodged onto the needles last mentioned, substantially as described. 160

In testimony whereof, I affix my signature.
KENNETH HOWIE.
